US0D1062401S

(12) **United States Design Patent** (10) **Patent No.:** **US D1,062,401 S**
(45) **Date of Patent:** **** Feb. 18, 2025**

(54) **FRUIT BASKET**

(71) Applicant: **Fuzhou Huodan Technology Co., Ltd.**,
Fuzhou (CN)

(72) Inventor: **Yixuan Xu**, Shenzhen (CN)

(73) Assignee: **Fuzhou Huodan Technology Co., Ltd.**,
Fuzhou (CN)

(**) Term: **15 Years**

(21) Appl. No.: **29/968,106**

(22) Filed: **Oct. 15, 2024**

(30) **Foreign Application Priority Data**

Sep. 23, 2024 (CN) 202430605413.7

(51) **LOC (15) Cl.** **07-01**

(52) **U.S. Cl.**

USPC **D7/704**

(58) **Field of Classification Search**
